UNITED STATES PATENT OFFICE.

GEORGE P. GRISWOLD, OF NEW ORLEANS, LOUISIANA.

DESIGN FOR A SPOON.

SPECIFICATION forming part of Design No. 21,051, dated September 22, 1891.

Application filed August 15, 1891. Serial No. 402,759. Term of patent 7 years.

To all whom it may concern:

Be it known that I, GEORGE PALFREY GRISWOLD, a citizen of the United States, residing at New Orleans, in the parish of Orleans and

5 State of Louisiana, have invented and produced a new and original Design for a Spoon, of which the following is a specification, reference being had to the accompanying drawing, forming part thereof.

10 The figure is a front view showing spoon in a vertical position.

The leading feature of my design for an orange-spoon consists in the bowl of spoon formed in shape of an orange-leaf with the

15 handle formed of leaves, flowers, and oranges. A is the bowl of spoon, which is shaped like an orange-leaf.

B is the handle of spoon, which is pressed in shape of an orange-branch, and C end or top of handle, which is formed of orange 20 leaves, flowers, and oranges.

What I claim is—

The design for an orange-spoon herein shown and described, the same comprising the orange-leaf-shaped bowl and the branch-shaped attachment of handle to bowl of spoon, having end of spoon-handle formed of leaves, flowers, and oranges, as set forth.

In testimony whereof I affix my signature in presence of two witnesses.

GEORGE P. GRISWOLD.
